SYSTEM OF ELECTRICAL DISTRIBUTIONS

Alfred C. Turtle, Montreal, Quebec, Canada

Application April 9, 1934, Serial No. 719,718

15 Claims. (Cl. 175—364)

This invention relates to systems of electrical distribution and particularly to the automatic regulation of load circuits, such as the lamp circuits of a railway car lighting system, whereby the voltage and wattage characteristics of each circuit is maintained approximately constant irrespective of a wide range of voltage fluctuations at the terminals of the current source from which the circuits are fed.

10 The primary object of this invention is the provision of improved voltage regulating means whereby the voltage across each of a plurality of circuits connected to a common variable voltage source may be maintained constant at a value either substantially above or substantially below the maximum voltage available at the terminals of said source.

Another object is the provision of voltage regulating means which is effective to maintain the voltage of each of said circuits constant throughout an exceptionally wide range of voltage fluctuations, in either direction, at the terminals of said source.

A further object is the provision of a self-regulating system of electrical distribution in which a plurality of circuits are supplied with alternating current from a direct current source through the agency of circuit regulating means that is also effective to maintain a constant potential difference across each circuit during a wide range of potential variations at the terminals of said direct current source.

A still further object is the provision of a self-regulating system of electrical distribution in which a plurality of circuits are supplied with alternating current from a direct current source through a regulating means effective to maintain the potential difference across each circuit constant during a wide range of potential variations at the terminals of said source and at a value either above or below the maximum potential available at said terminals.

A still further object is the provision of a self-regulating system of electrical distribution in which a plurality of circuits are supplied with alternating current from a direct current source through a rotary contactor by which each circuit is periodically shunted and then variably connected in series and in parallel with companion circuits; the duration of the shunted, series connected, and parallel connected periods of the circuits being automatically varied by the contactor in such relation to potential variations at the terminal of the direct current sources as to main-

tain an approximately constant potential across each circuit.

Fig. 1 is a view, in side elevation, of one form of contactor which may be utilized for regulating circuit voltage in accordance with the novel principle of this invention.

Fig. 2 is a sectional view along the line 2—2 of Fig. 1.

Fig. 3 is a view, in elevation, of the rotary element of the contactor.

Fig. 4 is a sectional view along the line 4—4 of Fig. 1, showing the arrangement of the brushes engaging the slip rings on the rotary element of the contactor. In this view certain parts are omitted for the sake of clearness.

Fig. 5 is a detail view showing the bracket which supports the contactor operating motor.

Fig. 6 is a diagrammatic view illustrating the manner in which the contactor is connected between the direct current source and the circuits.

Figs. 7 to 18 inclusive are diagrams illustrating the sequence of circuit connections established by the contactor during one revolution. In this view the illustrated length of the contactor brushes connected to the direct current source represents the minimum span of the brushes.

Figs. 19 to 30 are duplicates of Figs. 7 to 18 except that the illustrated length of the brushes appearing in Figs. 19 to 30 represents the maximum span of the brushes.

Fig. 31 is a table showing the manner in which the voltage amperage and wattage of each circuit is varied by the sequence of connections appearing in Figs. 7 to 18.

Fig. 32 is a table showing the manner in which the lengthening of the brushes, as illustrated in Figs. 19 to 30, varies the voltage, amperage and wattage values of the circuits as compared with Fig. 31.

Fig. 33 is a slight modification of the circuits appearing in Fig. 6.

According to the illustrated embodiment of this invention, a plurality of lamp circuits, of equal impedance or resistance, are fed from a direct current source through a rotary contactor which produces an alternating current in each circuit. The contactor also serves to repeatedly transpose the circuit connections so that each circuit, between periodic shunting periods preceding the reversal of current flow therein, is variably connected in series and parallel with companion circuits. The contactor is driven by a direct current motor at a speed which varies in direct proportion to potential variations at the ter-

5 minal of said direct current source to which the motor is connected. The positive and negative brushes of the contactor are automatically 10 adjusted, through the agency of a suitable governor, so that the effective length or span of each brush decreases when the motor speed increases and increases when the motor speed decreases. The circuit connections and the design 15 of the contactor are such that the shortening of the contactor brushes (which occurs when the motor speeds up in response to an increased voltage at the current source) serves to decrease the duration of the shunted and parallel-connected 20 periods of the circuits while increasing the duration of the series-connected periods. Similarly, the lengthening of the contactor brushes (which occurs when the motor speed decreases in 25 response to a voltage drop at the terminals of said source) serves to increase the duration of the shunted and parallel-connected periods of the circuits while decreasing the duration of the series-connected periods. By thus varying the duration of the shunting periods as well as the relative duration of the parallel and series-connected 30 periods of the circuits, the average potential, current and wattage values of each circuit may be kept approximately constant, within fairly wide limits, irrespective of potential variations at the terminals of the direct current source. As the lamp circuits are periodically 35 shunted and then connected in series and in parallel with each other, in various combinations, for varying lengths of time, depending on the potential variations at the terminals of the direct current source, there will be, of course, some compensating fluctuation in the voltage, amperage and wattage values of each circuit for each revolution of the contactor but the total effect will be the maintenance of approximately constant average 40 voltage and wattage characteristics for each circuit.

One embodiment of a motor driven contactor suitable for the purposes of this invention is illustrated in Figs. 1 to 5 inclusive. The motor 45 drives the contactor shaft 6 which is journaled in ball bearings 7 and 8. The bearing 7 is contained in the motor frame 9 which is fastened to the upper end of a bracket 10 rising from the base 11. The bearing 8 is enclosed by the housing 12 of a bracket 13 mounted on the base at the 50 end remote from the bracket 10.

A sleeve 14, made of insulating material, is fixed on the shaft 6 adjacent the bearing 8. Partially embedded in this sleeve are three insulated 55 slip rings designated 15, 16 and 17. Sleeve 14 also carries three partially embedded commutator segments 18, 19 and 20 which are spaced apart by interposed insulating segments 21. A stationary brush holder bracket 22, through which sleeve 14 extends, is mounted on the base 11 between the 60 three contact segments and the slip ring 15. Bracket 22 carries two diametrically opposite brush holders 23 and 24 containing brushes 23a and 24a (compare Figs. 1 and 2). These brushes are pressed against the contact segments 18, 19 65 and 20 and the interposed insulating segments 21 by suitable spring devices 25 forming part of the brush holders. The brushes 23a and 24a constitute the fixed positive and negative brushes with which the movable positive and negative 70 brushes 23b and 24b cooperate as hereinafter described.

The movable positive brush 23b (shown in full lines in Fig. 1 and by dotted lines in Fig. 2) is 75 slidably fitted in a brush holder 26 fastened to

a rotatably mounted adjusting ring 27. The movable negative brush 24b is similarly fitted in a brush holder 28 fastened to said ring diametrically opposite the holder 26. Each of the brushes 23b and 24b is pressed against the contact segments 18, 19 and 20 and the interposed insulating segments 21 by means of a spring device 29.

The adjusting ring 27 is rotatably supported by anti-friction balls 30 interposed between its outer edge and a surrounding bearing bracket 31, said balls being confined between two side plates 33 fastened in place as indicated at 34. Ring 27 is also connected to a governor 35 by means of which the ring is rotated in one direction or another in response to a change in the 15 operating speed of the motor 5. As illustrated, the connection between the ring and governor comprises a bell crank 38 having one arm 39 connected to the ring by a universal connecting link 40 and the other arm 41 connected to the movable end member 42 of the governor by a link 43, which works between ball bearings 44 at each of its connected ends. The ring 27 and bearing bracket 31 are preferably provided with coacting stop members 45 and 46 to limit rotation of the 25 ring in one direction.

Assuming an increase in the operating speed of the motor, the ring 27 will be turned as indicated by the arrow in Fig. 2 to shift the movable positive and negative brushes toward the cooperating 30 fixed positive and negative brushes to which they are electrically connected as hereinafter explained. This adjustment therefore results in a decrease in the effective length or span of said positive and negative brushes. A decrease in 35 the speed of the motor produces the opposite effect since the ring 27 is then turned to shift the movable positive and negative brushes away from the fixed positive and negative brushes, thus increasing the effective brush length or span. The 40 turning movement of the ring in the brush shortening direction is limited by the stops 45 and 46 which may be adjusted to regulate the minimum brush length.

The electrical connection between the fixed 45 and movable positive brushes 23a and 23b comprises a pair of conducting plates 47 and 48 fastened to opposite sides of the stationary brush holder bracket 22. The plate 47 is at the side of bracket 22 opposite the brush holder 23 to 50 which said plate is electrically connected by the brush holder fastening screws 49. The remaining plate 48 is electrically connected to the plate 47 by the fastening screw 50 and is also engaged by a wiper contact 51 fixed to the brush holder 26 55 of the movable brush 23a. A similar electrical connection, not shown, is provided between the fixed and movable negative brushes 24a and 24b.

Each of the commutator segments 18, 19 and 20 is connected to one of the slip rings 15, 16 60 and 17. These connections may be made as indicated in Fig. 3 where the segment 18 is shown connected to the ring 15 by a conducting strip 52; the remaining segments 19 and 20 being respectively connected to the rings 16 and 17 by 65 strips 53 and 54.

The rings 15, 16 and 17 are respectively engaged by brushes 55, 56 and 57 mounted in suitable brush holders 58, 59 and 60 provided with spring devices 61 for holding the brushes to the 70 rings, said brush holders being also provided with terminals 62, 63 and 64.

The manner in which the contactor is connected between the direct current source and the lamp circuits is diagrammatically illustrated in 75

Fig. 6. As here shown the two electrically connected positive brushes 23a and 23b are connected, by way of conductor 66 and switch 67 with the positive terminal 68 of the direct current source represented by the battery 69 and the shunt wound charging generator 70. The electrically connected negative brushes 24a and 24b are connected, by way of conductor 71 and switch 67 with the negative terminal 72 of the direct current source. The commutator segments 18, 19 and 20 are respectively connected, by way of the conductors 52, 53 and 54, with the slip rings 15, 16 and 17.

We come now to the connection of the lamp circuits indicated at A, B and C.

One side of circuit A is connected to commutator segment 18 by way of conductor 73, slip ring brush 55, slip ring 15 and conductor 52; the other side of said circuit being connected to the commutator segment 19 by way of conductor 74, slip ring brush 56, slip ring 16 and conductor 53.

One side of circuit B is also connected with commutator segment 19 by way of conductor 74, slip ring brush 56, slip ring 16 and conductor 53; the other side being connected to commutator segment 20 by way of conductor 75, slip ring brush 57, slip ring 17 and conductor 54.

One side of the remaining circuit C is connected to commutator segment 18 by way of conductor 73, slip ring brush 55, slip ring 15, and conductor 52; the other side being connected to commutator segment 20 by way of conductor 75, slip ring brush 57, slip ring 17 and conductor 54.

The motor 5, which operates the contactor shaft 6, is also connected to the terminals of the direct current source by the conductors appearing at 5a and 5b in Fig. 6.

The voltage regulation obtained by adjusting the span of the positive and negative brushes engaging the commutator segments to which the circuits A, B and C are connected is best explained by reference to the diagrams of Figs. 7 to 30 and the tabulations of Figs. 31 and 32. For the purpose of this explanation it is to be understood:

1. That the resistance of each of the circuits A, B and C is 5 ohms.

2. That a constant E. M. F. of 10 volts is impressed on the said positive and negative brushes by the direct current source which, in order to avoid unnecessary duplication, is shown only in Fig. 7.

3. That the minimum span of said positive and negative brushes is represented in Figs. 7 to 18 while the maximum span is represented in Figs. 19 to 30.

4. That the appearance of the mark 0 in association with a circuit indicates shunting of said circuit.

5. That the appearance of the mark $\rightarrow$ in association with a circuit indicates that said circuit is connected in series with one of the companion circuits which is similarly identified, the direction of flow being toward the arrow head.

6. That the appearance of the mark $\rightarrow$ in association with a circuit indicates that said circuit is connected, in parallel, with one or both of the companion circuits.

7. That, for convenient illustration, the commutator segments 18, 19 and 20 are represented as being stationary while the engaging positive and negative brushes are represented as traveling relatively to said segments.

In Fig. 7 the positive brush is bridging the commutator segments 18 and 19 while the negative

brush is engaging the segment 20. Circuit A is thus shunted while circuits B and C are connected in parallel with each other. As indicated in column D of Figure 31 this condition persists for a length of time corresponding to 4 degrees of a complete revolution of the brushes. (In actual practice this would correspond to 4 degrees of a complete revolution of the rotatably mounted commutator segments appearing in Figs. 1 to 6 inclusive.) It therefore follows that, as indicated in columns D and E of Fig. 31, the potential difference across each of the circuits B and C is 10 volts, producing a current flow of two amperes and a wattage value of 80. The next position of the brushes is represented in Fig. 8, the circuit connections now established persisting for a period of time corresponding to 56 degrees of a complete revolution of the brushes. In this case the circuits A and B are connected in series with each other and in parallel with circuit C, the resulting change in the voltage, amperage, and wattage values of the circuits being indicated in the aforesaid columns D and E of Fig. 31. The circuit connections subsequently established by the brushes as they complete one revolution, being clearly indicated in Figs. 9 to 18 inclusive, will be briefly referred to as follows:—In Fig. 9 circuit B is shunted while circuits A and C are connected in parallel with each other; in Fig. 10 circuits B and C are connected in series with each other and in parallel with circuit A; in Fig. 11, circuit C is shunted while circuits A and B are connected in parallel with each other; in Fig. 12 circuits A and C are connected in series with each other and in parallel with circuit B; in Fig. 13 circuit A is again shunted while circuits B and C are connected in parallel with each other; in Fig. 14 circuits A and B are again connected in series with each other and in parallel with circuit C; in Fig. 15 circuit B is again shunted while circuits A and C are connected in parallel with each other; in Fig. 16 circuits B and C are again connected in series with each other and in parallel with circuit A; in Fig. 17, circuit C is again shunted while circuits A and B are connected in series with each other; in Fig. 18 circuits A and C are again connected in series with each other and in parallel with circuit B. The manner and extent to which the voltage, amperage and wattage values of the circuits are varied by the last mentioned sequence of connections is indicated under the appropriate headings in columns D and C of Fig. 31. By studying the figures in these columns, in conjunction with the showing of Figs. 7 to 18 inclusive, it will be seen that, for each complete revolution of the brushes, each circuit is shunted for a total period of time corresponding to 8 degrees of brush revolution; is connected in parallel for a total period of time corresponding to 128° and is connected in series for a total period of time corresponding to 224°. Since a constant E. M. F. of 10 volts is impressed on the brushes and since the resistance of each circuit is 5 ohms it follows that the potential difference across each circuit will be zero for 8°; five volts for 224° and ten volts for 128° and that the wattage will vary accordingly. When the positive and negative brushes are lengthened to their maximum span as represented in Figs. 19 to 30 the sequence of circuit connections remains the same as in Figs. 7 to 18 but the duration of the series-connected periods of each circuit is decreased while the duration of the shunted and parallel-connected periods is increased. The effect of this with respect to varying the voltage and wattage characteristics of 75

the circuits will be apparent from a comparison of the tabulations in Fig. 32 with those in Fig. 1, which clearly shows that, with the voltage impressed on the brush terminals remaining constant, the voltage and wattage values of the circuit may be varied approximately 30 per cent by full range adjustment of the span of said brushes.

In accordance with the purpose of the present invention, the aforesaid circuit regulating effect of the brush-span adjustment is utilized to maintain the voltage and wattage characteristics of the circuits approximately constant throughout a wide range of potential variations to be expected across the terminals of the direct current source under actual service conditions. This is accomplished through the agency of the previously described motor operated governor mechanism which automatically shifts the movable brush members so that the duration of the shunted, series-connected and parallel connected periods of the circuits is varied in such relation to the potential changes of the direct current source as to maintain the voltage of each circuit at a predetermined constant value which may be substantially above or substantially below the maximum value of the fluctuating direct current source voltage. It will thus be seen that the voltage regulating means of the present invention is adapted to take care of a wide range of variations either above or below the normal voltage of said source.

In regard to the structural design of the contactor it will be understood that the length of the commutator segments 18, 19 and 20 and the interposed insulating segments 21, as well as the minimum and maximum span of the engaging adjustable brushes, are variable factors which may be predetermined to suit particular installations, it being important however that the minimum span of the brushes should be somewhat greater than the spacing of adjacent segments. It will also be understood that, in applying the principles of this invention, the number of contactor segments and the number of circuits controlled by the contactor may be varied.

In Fig. 33 there is shown a slight modification in which auto transformers, appearing at T, T' and T'', are respectively included in the lamp circuits A, B and C, to step up the voltages of said circuits with respect to the voltage impressed on the brushes. Transformers comprising separate primary and secondary windings with the usual interlinking alternating magnetic flux can also be used in place of the transformers illustrated herein.

In Figs. 7 to 32 it has been shown that, when using a constant voltage direct current source, the energy input may be decreased or increased by shortening and lengthening the effective span of the positive and negative brushes. It will therefore be seen that by regulating the span of the brushes independently of the voltage across the terminals of the supply source, a wide range of control may be exercised with respect to the energy input to the lamp circuits.

In order to eliminate or diminish sparking between the commutator segments and the engaging brushes of the circuit controller when dealing with currents of high amperage, it is proposed to enclose the assembly appearing in Fig. 1 within a gas-tight casing 11a filled with air or gas under appreciable pressure. In this case the battery and circuit leads will be connected through the agency of pressure-tight terminals passing through the base 11.

Having thus described my invention, what I claim is:—

1. A system of electrical distribution comprising, in combination, a direct current source, a plurality of circuits, and circuit connecting means through which all of said circuits are connected to said source, said connecting means acting automatically to repeatedly transpose the circuit connections to produce an alternating current in each circuit and to connect each circuit in varying series and parallel relation with companion circuits between shunting periods of said circuit preceding a reversal of the current flow therein, and means for automatically regulating the action of said connecting means to vary the duration of the shunted, series-connected, and parallel-connected periods of each circuit in such relation to voltage variations at the terminals of said source as to maintain the voltage characteristics of each circuit approximately constant. 20

2. A system of electrical distribution comprising, in combination, a direct current source, a plurality of circuits, and circuit connecting means through which all of said circuits are connected to said source, said connecting means acting automatically to repeatedly transpose the circuit connections to produce an alternating current in each circuit and to connect each circuit in varying series and parallel relation with companion circuits between shunting periods of said circuit preceding a reversal of the current flow therein, and means for automatically regulating the action of said connecting means to vary the duration of the shunted, series-connected, and parallel-connected periods of each circuit in such relation to voltage variations as the terminals of said source as to maintain the voltage characteristics of each circuit approximately constant at a predetermined value which may be either substantially above or substantially below the maximum voltage delivered by the direct current source. 35

3. A system of electrical distribution comprising, in combination, a direct current source, a plurality of circuits, and a rotary contactor connected between said source and said circuits, said contactor functioning to produce an alternating current in each circuit; to periodically shunt each circuit; and, between shunting periods, to connect each circuit in series and parallel with companion circuits; and means for adjusting said contactor to shorten and lengthen the shunted, series-connected and parallel-connected periods of said circuits in response to potential variations at the terminals of said source and in such relation to said variations as to maintain an approximately constant voltage across each circuit. 55

4. A system of electrical distribution comprising, in combination, a direct current source, a contactor including a series of rotary contact segments and engaging positive and negative brushes, said brushes being respectively connected to the corresponding terminals of said source, a plurality of circuits connected to said segments so that, during rotation of the segments relative to the brushes, each circuit is periodically shunted and, between shunted periods, is variably connected in series and in parallel with the companion circuits, and means for adjusting the effective span of said brushes to vary the duration of the shunted, series-connected and parallel-connected periods of said circuits. 65

5. A system of electrical distribution comprising, in combination, a source of direct current, a plurality of circuits, a contactor connected be- 75

5 tween said source and said circuits, said contactor functioning to produce an alternating current in each circuit; to periodically shunt each circuit; and to variably connect each circuit, between its shunted periods, in series and in parallel with 10 companion circuits, and means for adjusting said contactor to vary the duration of the shunted, series-connected and parallel-connected periods of each circuit and thereby "step up" or "step down" the potential across each circuit with respect to the potential across the terminals of the direct current source.

10 6. A system of electrical distribution comprising, in combination, a direct current source, a 15 plurality of circuits, a circuit controller through which all of said circuits are connected to said source so that, during operation of the controller, each circuit is periodically shunted and, between shunted periods, is connected in varying series 20 and parallel relation with companion circuits, a motor driving said controller and connected so that the speed of the motor varies in direct proportion to potential variations at the terminals of said source and controller adjusting means acting 25 automatically, in response to changes in the operating speed of the motor, to vary the duration of the shunted, series-connected, and parallel relation of the circuits in such relation to the potential changes at the terminals of the 30 direct source as to maintain an approximately constant voltage across each circuit.

35 7. A system of electrical distribution comprising, in combination, a direct current source, a circuit controller comprising a commutator and engaging variable-span positive and negative 40 brushes, said brushes being respectively connected to the corresponding terminals of said source, a plurality of circuits connected to said commutator so that, during relative movement between the 45 commutator and brushes, each circuit is periodically shunted and, between shunted periods, is connected in series and in parallel with companion circuits, and means responsive to potential changes at the terminals of said source for adjusting the span of said brush to vary the 50 duration of the shunted, series-connected and parallel-connected periods of the circuits, in such relation to said potential changes as to maintain an approximately constant voltage across each circuit.

55 8. A system of electrical distribution comprising, in combination, a direct current source, a motor connected to said source to operate at a speed directly proportional to the potential across the terminals of said source, a circuit controller, 60 driven by said motor, comprising a commutator and engaging variable-span positive and negative brushes, said brushes being connected to the corresponding terminals of said source, a plurality of circuits connected to the segments of said commutator so that each circuit is periodically shunted and then variably connected to said source in series and parallel relation with companion 65 circuits, and a governor operating, in response to changes in the speed of said motor, to adjust the span of said brushes to vary the duration of the shunted, series connected, and parallel connected periods of said circuits, in a manner compensating for the changes in potential producing the 70 aforesaid changes in the speed of the motor.

75 9. A system of electrical distribution as claimed in claim 3 including a casing enclosing said ro-

tary contactor and containing a gaseous medium under pressure.

10 10. A system of electrical distribution comprising, in combination, a direct current source, a plurality of circuits, and circuit connecting means through which all of said circuits are connected to said source, said connecting means including an interrupter mechanism functioning to repeatedly transpose the circuit connections to produce an alternating current in each circuit and 15 to connect each circuit in varying series and parallel relation with companion circuits, and means for adjusting said interrupter mechanism to vary the duration of the series-connected and parallel-connected periods of each of said circuits. 15

15 11. A system of electrical distribution comprising, in combination, a direct current source, a plurality of circuits and an adjustable rotary contactor connected between said source and said circuits, said contactor functioning to produce an 20 alternating current in each circuit and to connect each circuit in series and parallel with companion circuits and means for adjusting said contactor to shorten and lengthen the series-connected and parallel-connected periods of said cir- 25 cuits.

12. A system of electrical distribution comprising, in combination, a direct current source, a plurality of circuits, a circuit controller through which all of said circuits are connected to said 30 source so that, during operation of the controller, each circuit is connected in varying series and parallel relation with companion circuits, a motor driving said controller and controller adjusting means acting automatically in response to changes 35 in the operating speed of the motor to vary the duration of the series-connected and parallel-connected periods of said circuits.

13. Electrical apparatus for supplying alternating current of approximately constant potential to each of a plurality of load circuits comprising, in combination, a direct current source, a contactor including a series of contact segments and engaging positive and negative brushes, said brushes being respectively connected to the corresponding terminals of said source, means including an electric motor for effecting relative movement between said contact segments and said brushes and means for adjusting the effective span of said brushes in response to changes 50 in the speed of the motor.

14. Apparatus as claimed in claim 13 in which the motor is connected to the direct current source so that its operating speed varies in direct proportion to potential variations at the terminals 55 of said source.

15. Apparatus for use in supplying alternating current of approximately constant potential to each of a plurality of load circuits comprising, in combination, a direct current source, a plurality of 60 transformers and circuit connecting means through which the primary circuits of all of said transformers are connected to said source, said connecting means including an interrupter mechanism functioning to repeatedly transpose the 65 circuit connections to connect each of said primary circuits in vary series and parallel relation with companion primary circuits and means for automatically adjusting said interrupter mechanism to vary the duration of the series- 70 connected and parallel-connected periods of said circuits.

ALFRED C. TURTLE.
